UNITED STATES PATENT OFFICE.

CHARLES H. COONS, OF SAUGERTIES, NEW YORK, ASSIGNOR TO THE TISSUE COMPANY, OF SAUGERTIES, NEW YORK, A CORPORATION OF NEW YORK.

NAPKIN DISPENSER.

Application filed July 21, 1928. Serial No. 294,541.

This invention relates to napkin dispensers, and has for an object to provide an improved construction wherein folded napkins are held properly in position for vending.

5 Another object of the invention is to provide a napkin folder or dispenser wherein means are provided which will cause the edges or certain sections of the napkin to project outwardly from the holder, whereby 10 the napkin may be readily grasped.

A still further object, more specifically, is to provide a holder and vending apparatus with rounded apertured portions and swinging weights for forcing folded napkins toward the apertured portions in such a manner that the napkins will be caused to buckle and open the folded sections.

In the accompanying drawings,—

Figure 1 is a perspective view of a napkin 20 dispenser disclosing an embodiment of the invention;

Figure 2 is an enlarged vertical sectional view through Figure 1;

Figure 3 is a transverse sectional view 25 through Figure 2 on the line 3—3;

Figure 4 is a fragmentary sectional view through Figure 2 on the line 4—4;

Figure 5 is a perspective view on a reduced scale with one of the folded napkins 30 shown in Figures 1 and 2.

Referring to the accompanying drawing by numerals, 1 indicates a casing preferably of metal and preferably substantially rectangular, but provided on the front and rear faces with rounded panels 2. The top and bottom respectively are provided with projections 3 coacting with the panels 2. Each of the panels 2 is provided with an opening or cut-away portion 4 which is somewhat enlarged at the center, namely, at point 5, whereby the hand of a person may more readily grasp the edges 6 and 7 of the sections 8 and 9 of the folded napkin 10. The napkin 10 is made of paper of any desired kind and folded as clearly set forth in the co-pending application of C. H. Coons, whereby the sections 8 and 9, when released, will spring upwardly, as shown in Figure 5, or when the napkin is closed on a vertical 45 central line, will spring outwardly, as indicated more particularly in Figure 3. In order that the sections 8 and 9 may move outwardly and particularly the edges 6 and 7, so that they will assume the position shown in Figure 3, the panels 2 are decidedly 55 rounded and the respective packages or bunches 11 and 12 of napkins are forced toward these panels by the lower ends 13 and 14 of the weights 15 and 16. These weights are formed as right angle members with extensions 17 and 18 projecting through suitable apertures in the side plates 19 and 20. The side plates 19 and 20 are soldered, welded or otherwise secured to the casing 1 and act as journal members for the weights 60 and guides for the bundles of napkins.

As indicated particularly in Figure 4, the lower ends of the weights are rounded and thereby engage somewhat centrally the bunches of napkins to force the same outwardly in a rounded position, so that the edges 6 and 7 of the outermost napkins will curl outwardly slightly as the sections 8 and 9 somewhat expand. This permits a ready hand-hold for a person when removing a 65 napkin. In devices heretofore different folds have been provided, but in each instance it was necessary to press downwardly on the napkin in order to get the edge of the fold or a part of the napkin. By reason of 70 the particular fold and the way the members 2 are formed, the folded edges 6 and 7 are automatically held in a position to be readily grasped. As indicated particularly in Figure 75 3, the casing 1 is provided with suitable bent-out members 21 presenting runways for the respective members 2, so that these members may be slid into position and may be removed at any time in order that new batches or supplies of folded napkins may be 80 inserted. After a supply of napkins has been inserted, the dispenser is set up on end, as shown in Figures 1 and 2 and the weights 85 15 and 16 automatically swing so that the lower ends will press the napkins outwardly 90 and thereby produce the bulged or rounded formation shown in Figure 5. As the weights move the napkins to their curved 95 position, as shown in Figure 3, the outermost napkin automatically assumes the position with the edges 6 and 7 slightly turned outwardly. When the napkin is removed by grasping one of the edges 6 and 7 and then pulling the same the next napkin will automatically take its place and the edges will 100 automatically swing outwardly a short distance. This is caused largely by the shape 105 of members 2 and the action of the weights,

though augmented by the resiliency of the paper.

What I claim is:—

1. A napkin dispenser, comprising a casing open at the front and back from top to bottom, said casing along the edges of the opening being formed with turned-over portions presenting guiding grooves, an apertured arc-shaped panel for the front, an apertured arc-shaped panel for the rear, said panels being arc-shaped throughout, said panels being slidably mounted in said grooves and completely closing said opening, and a swinging weight arranged interiorly 15 of the casing for forcing part of the napkins carried by the casing into said apertures, whereby they may be readily grasped for removal.

2. A napkin dispenser, including a casing 20 having a rounded face for its entire area, said face having a comparatively large elongated opening extending from near the top to near the bottom, a substantially L-shaped weight arranged in the casing and means 25 for pivotally supporting said weight at one end of one of the legs thereof, whereby the opposite end of the other leg will press against napkins in the casing to force the same toward and into said opening, said 30 last-mentioned leg extending transversely

across the napkins for almost the full width of the napkins.

3. A napkin dispenser for dispensing folded napkins, comprising a casing, a plurality of rounded panels carried by the casing, each of said panels having centrally positioned openings extending from near the top to near the bottom thereof so as to expose napkins in the casing, an inner frame arranged in the casing and a pair of weights 35 pivotally carried by said frame, said weights having projections extending into said frame, said projections being so located that the end opposite the projections will automatically swing for forcing the napkins toward the openings in said panels. 40

4. A napkin dispenser for dispensing folded napkins, comprising a casing, a rounded panel carried by the casing, said panel having a centrally positioned opening 50 extending from near the top to near the bottom so as to expose napkins in the casing, an inner frame arranged in the casing and a weight pivotally carried by the frame, said weight having projections extending into said frame, said projections being so located that the end opposite the projections will automatically swing for forcing the napkins toward the opening in said panel. 55

CHARLES H. COONS.
